UNITED STATES PATENT OFFICE.

CARROL L. ETHERIDGE, OF JOPLIN, MISSOURI.

POST-WINDER.

SPECIFICATION forming part of Letters Patent No. 600,638, dated March 15, 1898.

Application filed August 10, 1897. Serial No. 647,740. (No model.)

To all whom it may concern:

Be it known that I, CARROL L. ETHERIDGE, a citizen of the United States, and a resident of Joplin, in the county of Jasper and State 5 of Missouri, have invented a new and useful Improvement in Post-Winders and Wire Fences, of which the following is a specification.

My improvement is directed to provision 10 whereby the line-wires of wire fences are combined with post-winders for keeping the wires taut and the fence in a firm condition; and the particular matter of my improvement will be set out in the claim concluding this specification.

In the accompanying drawings I have shown in Figure 1 a portion of a wire fence, one of the posts representing the anchor-post of the line-wires and having my improved 20 stretching-winders. Fig. 2 shows enlarged the link-stays and their connection with the line-wires. Fig. 3 is a vertical section of the same. Fig. 4 shows the anchor-post which contains the wire-stretching winders. Fig. 5 25 is a vertical section of the same, taken in the line of the post-winder. Fig. 6 is a like view showing the winder in cross-section. Fig. 7 is a horizontal section of the same, and Fig. 8 shows one of post-winders.

Each section of the fence has its line-wires 30 connected by vertical stay-wires, whereby to form a fence suited for large and for small stock. The vertical stay-wires may be of any suitable construction. As shown, they are 35 each formed of links 2, each link having an eye 3 at its end projecting at right angles on the same side of the fence, so that the eyed ends of the connecting-links stand in opposite directions to each other. The eyed end 40 of one link is engaged with the eyed end of the other link; but the eyes are not engaged with each other, so that the end of one link is free to slide upon the end of the other link. It is between the eyed ends of the links thus 45 coupled that the line-wires pass and over which each link is free to slide between their eyed ends. In tightening the line-wires the stays are kept in proper bracing relation to them, making a strong and firm fence, and to 50 the line-wires of which the stays may be suitably tied to prevent them from being moved apart on the line-wires. The links may be

coupled by eye-joints 5 between the line-wires. Any desired number of line-wires may be used and the links may be close 55 enough together to prevent hogs or other small stock from spreading them or the line-wires. At the bottom of the fence the line-wires are placed closer together. This construction renders it possible to build a firm 60 fence from seventy-five to one hundred feet between the posts.

In erecting the fence the line-wires are passed through holes and keyed or otherwise secured in the post at the beginning of the 65 line and thence passed up through the line-posts to the end post, into which they are passed through holes 6, opening on one side and secured to winders fitted into the post, as I will now describe. The end post has 70 bores 7 made in it from one side, but preferably not extending through it, and for each line-wire there is a hole 6 in one side of the post intersecting the bores 7. Into these bores are fitted hollow plugs 8, so that their 75 ends stand out to the side of the post and in position at right angles to the line-wires. These hollow plugs are slotted lengthwise at each end, and preferably these slots 9 and 10 are made at right angles to each other, as 80 seen in Fig. 8. All the line-wires having been passed into the holes 6 in the post are passed through the slot 9 at the inner end of the plug and into and through the plug to its outer end. The plugs have each a circum- 85 ferential recess 11 at the inner slotted ends, and it is within these recesses that the line-wires are wound upon the plugs when they are turned to stretch and tighten the wires. These recesses are sufficiently deep to give 90 room for this purpose, so that the plugs are not bound in the bores, but are free to be turned to wind the wires as it may be necessary to tighten them. When so stretched and tightened, the end of each wire, which is 95 pulled out through the slot 10 in the outer end of the plug, is wrapped to tie it around the plug. When so tied, the plugs are locked to the posts by pins 13, which merely engage the slots 9 at the inner ends of the plug. For 100 the convenient insertion of these pins that side of the post opposite to the receiving-holes for the line-wires has slots 14, which open into the bores 7, so that it is only necessary

to turn the plug that these slots may coincide with the post-slots to push the pins into the post-slots, with the pins resting against the edge of the slot which locks the plugs, and 5 leaves the pins easy to remove for winding and tighten the wires as may be needed and the pins replaced.

In tightening the line-wires it is important that the winding-plugs be free to be turned 10 and that the locking-pins for the plugs be free for removal. Hence the provision of the recessed body of the plug within which to wind the wire on the plug and the slots in the post for conveniently inserting a pin for 15 locking the winding-plugs and thereby rendering it easy work to keep the fence-wires tight.

I claim—

In a wire fence, the combination with the line-wires, the fence-post having holes in one 20 side for receiving the line-wires, its opposite side having horizontal transverse slots, and bores parallel with and opening into said slots and intersecting said holes, with hollow winding-plugs having slots at each end and circumferentially recessed and fitted within said bores at right angles to the line-wires, and pins inserted into the post-slots and into the plug-slots in a way to rest against the slot-walls to lock the winder to maintain the wires 25 30 taut.

CARROL L. ETHERIDGE.
